UNITED STATES PATENT OFFICE.

WILLIAM STUART WEBSTER, OF ROSLINDALE, MASSACHUSETTS, ASSIGNOR TO WIRELESS SPECIALTY APPARATUS COMPANY, OF BOSTON, MASSACHUSETTS, A CORPORATION OF NEW YORK.

COMMUNICATION DEVICE.

Application filed January 10, 1923. Serial No. 611,723.

This invention relates to communication devices.

The object of the invention is to provide a standard connection between a communication receiving set (such as a radio receiving set) and electric mains such as those to an electric lighting system, whereby the normal currents on the mains will be prevented from access to the communication receiving set, while the communication currents carried by the mains can pass readily to the receiving set.

The invention consists of the construction and arrangements hereinafter described and claimed, and shown in the drawings, of which

Figure 1 is an elevation in part section of the completely assembled device;

Fig. 2 is a diagram of the interior and exterior circuit connections, showing the mode of use of the device;

Fig. 3 is a central horizontal section along line 3—3 of Fig. 1;

Fig. 4 is an elevation of the left end of the device shown in Fig. 1;

Fig. 5 is a section at 5—5 of Fig. 3, looking in the direction of the arrows;

Fig. 6 is a section at 6—6 of Fig. 3, looking in the direction of the arrows;

Fig. 7 is a section at 7—7 of Fig. 3, looking in the direction of the arrows, the section showing in elevation one of the two insulating members of the casing of the device;

Fig. 8 is a perspective expanded view of the condenser 23—23 of Fig. 2, shown inside the device in Fig. 3, Fig. 8 showing the arrangement of dielectric and conducting sheets in the condenser;

Figs. 9 and 10 are an elevation and plan of a condenser clamping plate and binding post terminal;

Figs. 11 and 12 are an elevation and section of the spring clamping plate of the condenser of the device; and

Fig. 13 is a top plan view of condenser 23 assembled with its clamping plates in final form as shown in Fig. 3, and comprising the parts shown in Figs. 8—12.

As shown in Figs. 1, 3 and 4, the device has a general resemblance to the ordinary electric lighting plug adapted to be screwed into the ordinary wall lighting socket,—the left end of the insulating structure having

the form of a cylindrical plug on the outside of which is located a threaded sleeve contact S and an end contact P adapted to engage corresponding contacts in the lighting socket. This device also is provided with a binding post BP at its opposite or enlarged end, and from this a connection may be made to the radio or other receiving apparatus as shown at the right in Fig. 2, so that the device itself with the electric mains to which it is connected may serve in lieu of special aerial wires or receiving loops.

In Fig. 2, the binding post is shown at BP and connected to the primary of a transformer T of the receiving set on the way to earth E via condenser C. The local circuits of the receiving apparatus may comprise any desired arrangement such as that shown elementally as including the secondary of transformer T, variable tuning condenser C¹, detector D, telephones PH and telephone-condenser C².

In Fig. 2, the screw-sleeve contact is shown at S, and the end contact of the plug at P. The condenser, which is located inside the device, is shown at 23, 23. When the device is screwed into a socket, contact-sleeve S is connected by house main L¹ to one side L of the line, such as a lighting circuit, and end contact P is connected through house wiring L² with the other side EL of the lighting main. (One of the mains may be ground, as is frequently the case.) Electrical connection 1 is provided between contact-sleeve S and condenser 23, and connection 2 is provided between end contact P and another part of condenser 23. From a third part of the condenser a connection is provided to binding post BP, and this connection may be from a midpoint M of the condenser. The condenser may be in two parts, i. e., there may be two separate condensers connected together; but, for convenience, as a practical matter, it is preferred to have a single condenser, with suitable connections therefrom, so that there may be some capacity between the binding post BP and each side of the lighting mains; for by this arrangement, the lighting currents will be confined to the mains, but the communication currents may pass through the capacity and binding post to the receiving set. The communication cur-

rents are usually of high frequency and may be impressed directly on the mains or may be set up therein by radio transmissions.

5 The assembly is shown in Fig. 3. The device, as shown in its preferred form, comprises two members A and V of suitable insulating material, such as porcelain or molded composition, constructed as shown 10 to form a housing in the end of the device which has larger diameter. In the interior space is mounted the condenser having the elements shown in Fig. 8 and the clamping means shown in Figs. 9-12, assembled in 15 Fig. 13. From the condenser a lead 1 (Fig. 3) extends to a brass insert 26, to which it is soldered. Engaging in the member 26 is a threaded bolt 27 which provides electrical connection with contact-sleeve S and 20 holds the latter in place. A second screw 27 also holds sleeve 28 in place, by engagement with a nut 28. Nut 28 and insert 26 are located in recesses F in insulating member A. Another portion of the condenser 25 is connected by lead 2, extending through a central hole 2^a (Figs. 4 and 5) in the plug portion of insulating member A, to a brass insert 2^b in the end of the plug. The end of lead 2 is clamped between insert 2^b and 30 washer 5 by the end contact P, which is in the form of a screw which enters insert 2^b (Figs. 3 and 4). Nut 28 may be electrically separated from lead 2 by a sheet of mica 29 or other insulation mounted to intervene 35 (Figs. 3 and 5). Brass insert 2^b is molded into end projection G (Figs. 3 and 4) of insulating member A.

Insulating members A and V are secured together by two screws 3 (Figs. 4-7) which 40 extend through holes molded in interior projections of members A and B (Figs. 5, 6 and 7). The condenser is clamped between metal members 8 and 14 shown as plates in Figs. 9 and 11 and in assembly in Fig. 13. 45 These plates are held in clamping position by bolts 15 and nuts 16. Plate 14 is of spring steel made to be normally bowed (Fig. 12) so that, when clamped in place (Fig. 13), its central part exerts a yielding 50 pressure on condenser-mica-stack 23. To metal clamping plate 8 (Fig. 9), a threaded post 9 (Fig. 13) is riveted at R (Figs. 9 and 10). The interior of insulating casing cover V is formed with a boss B¹ (Fig. 7), 55 against which clamping member 8 abuts. The clamped condenser (Fig. 13) is secured against boss B¹ (Fig. 3) by nut 10 outside the device. Beyond nut 10 are suitable brass washers 11. The threads of rod 9 are 60 extended to receive binding screw BP.

The construction of the condenser and the preferred mode of its connections are as follows. The dielectric and conducting sheets comprise alternately-disposed sheets of mica 65 and lead foil. In the specific example

shown, there are nine mica sheets N and nine foil sheets to be described. In Fig. 8, the bottom corresponds to the left side of the condenser in Fig. 3. The arrangement in general is such that the connection of binding post BP to the condenser is at a point of the condenser intermediate the two connections thereto from contacts S and P respectively. The five foil sheets marked Z (Fig. 8) extend on both sides beyond the 70 stack of mica sheets N. These five foil sheets Z are soldered at their opposite projecting ends to bolts 15 (Fig. 13) of the clamping means. These sheets Z are the ones projecting toward the observer in Fig. 80 3. The two foil sheets marked X (Fig. 8) project from the left of the stack of mica sheets N in Fig. 8 (from the top, Fig. 3) and are soldered to condenser lead 1 (Fig. 3), at the top, leading to sleeve-contact S 85 of the device (see diagram, Fig. 2). The two foil sheets marked Y (Fig. 8) project to the right beyond the stack of mica sheets N and in Fig. 3 extend downward and are soldered to condenser lead 2, leading to end 90 contact P of the device. Although this condenser is not a high potential condenser, yet, if desired, one or more extra mica sheets 95 may be placed between the condenser and its metallic clamping plates 8 and 14. As stated, the connection of the condenser to post 9 and binding screw BP is by way of the soldering of foil sheets Z to bolts 15 (Fig. 13). The capacity of the entire condenser is .001 mfd.; and in the arrangement 100 described the capacity between the binding post and each of contacts S and P is .002 mfd. As shown (Fig. 3), the condenser within the housing formed by insulating members A, V, is imbedded in paraffin; and 105 this may be done by filling the hollow part of each of members A and V with paraffin and then bringing and securing the two members together, and tightening up nut 10 against the washer Q. But in practice it is 110 easier simply to varnish the condenser and let it occupy an air space inside the casing. In any event, the condenser is processed in any suitable manner involving the use of paraffin wax and high mechanical pressure 115 to secure intimate contact of the sheets, before being finished with the covering of varnish.

Fig. 4 shows the completed device, with contact-sleeve S and end contact P in place,—the screws 3 securing insulating member A of the casing to casing-cover V, and wire lead 2 emerging from hole 2^a in projection G of insulating member A, and entering beneath washer 5 where it is held 120 by screw contact P. Contact P, of course, is adapted to engage the central contact of the lighting socket.

Fig. 5 shows the interior of member A, and Fig. 7 the interior of insulating member 125

V, illustrating the construction, with molded annular rims B, whereby the two members together form a housing for the condenser at their meeting ends. Fig. 7 shows member V without the condenser attached against boss B¹, the section being taken through clamping bolts 15. Fig. 6 shows the condenser secured by bolts 15 to cover V of Fig. 7, the condenser lying within the enclosure of casing A. In Fig. 6, foils X are shown projecting at the top, adapted for soldering to lead 1 of Fig. 3. At the bottom (Fig. 6), condenser sheets Y depend in readiness for soldering to lead 2 of Fig. 15. In Fig. 6 conducting sheets Z are shown projecting at opposite sides for soldering to clamping bolts 15, as shown in Fig. 13.

This device provides a convenient standard means consisting of a single assembled unit whereby the operator or user of a radio receiving set or the like may provide himself with an operating antenna merely by screwing the device into a lighting socket and attaching to binding post BP a lead to his receiving apparatus.

The invention is not to be considered as limited by the description or drawings.

I claim:

1. An electrostatic device which comprises two insulating members secured together and constructed to form an enclosed space between their meeting ends; an electrical sheet condenser located in said space; condenser clamping means also located in said space; an end contact and a sleeve contact exposed at one end of the device, and a binding post exposed at its other end; and electrical connections between said condenser, end contact, sleeve contact and binding post whereby a part of the capacity of the condenser is included permanently between the end contact and the binding post, and another part between the sleeve contact and the binding post, the end contact and the sleeve contact being connected respectively to the opposite end terminals of the condenser.

2. An electrostatic device which comprises two insulating members secured together and constructed to form an enclosed space between their meeting ends; an electrical condenser located in said space; two contacts exposed at one part of the device and a binding post exposed at another part; said condenser comprising alternate sheets of dielectric and conductor; an electrical connection from one of said exposed contacts to a plurality of conducting sheets of said condenser; an electrical connection from the other of said exposed contacts to a plurality of conducting sheets of said condenser which alternate with the conducting sheets to which the first exposed contact is connected; and an electrical connection from said binding post to conducting sheets of the

condenser which lie between said alternating sheets which are connected respectively to the two exposed contacts.

3. An electrostatic device which comprises two insulating members, on one of which are exteriorly mounted two contacts and on the other of which is mounted a binding post; an electrical sheet condenser and means for clamping the same, both mounted inside the device and having its mid-point connected with the binding post; a connection between the condenser and each of said contacts, both of said connections extending thru perforations thru one of said insulating members; and means for securing together the two insulating members.

4. An electrostatic device which comprises two insulating members constructed to form an enclosed space between their meeting ends; an electrical condenser and means for clamping the same, both located in said space; two contacts exteriorly exposed at one part of the device and a binding post exteriorly exposed at another part; an electrical connection between one of said contacts and the condenser, said connection securing said contact to one of said insulating members; an electrical connection between the condenser and the binding post; means securing said contacts and binding posts in place; and means independent of said electrical connections and securing means for securing the two insulating members together.

5. An electrostatic device which comprises an electrical condenser; an insulating enclosing casing therefor; condenser clamping means also located inside said casing; two contacts and a binding post exteriorly mounted on said casing; means for electrically connecting said contacts across the entire capacity of said condenser; and means for electrically connecting said binding post to a part of the condenser intermediate of the parts which are connected to said contacts.

6. An electrostatic device which comprises an electrical condenser; an insulating casing therefor comprising two members constructed to form a housing between them, the condenser being supported in said housing; a wax filling around the condenser in the housing; two contacts and a binding post exteriorly mounted on the casing; and electrical connections between the condenser, contacts and binding post whereby parts of the capacity of the condenser are included respectively between the binding post and the two contacts.

7. An electrostatic device which comprises an insulating housing consisting of two members secured together and having two contacts mounted exteriorly at one end and a binding post also exteriorly mounted thereon; a condenser located in said housing;

- condenser clamping means also located inside said housing; and connections inside the device to include the capacity of the condenser between a contact and the binding 5 post.
8. An electrostatic device which comprises an insulating contact-carrying portion and another insulating portion carrying a condenser and a binding post; two contacts 10 mounted exteriorly of the first portion; the condenser and the binding post being mounted respectively interiorly and exteriorly; and the condenser being enclosed between said two insulating portions; an 15 electrical connection between the binding post and the condenser; means inside the housing for clamping the condenser; and means for electrically connecting the condenser with the contacts.
9. An electrostatic plug, which comprises an electrical condenser; an enclosure therefor consisting of an insulating casing and an insulating cover therefor; said enclosure being extended at one end in the form of a 20 plug for a socket; clamping means for the condenser; a binding post structure combined with the clamping means and extending out of the cover of the enclosure; a screw-sleeve contact and an end contact 25 mounted exteriorly on the plug portion of the enclosure; and electrical connections inside the casing whereby the condenser is included between the binding post and the respective plug contacts.
10. An electrostatic device which comprises an insulating plug-in structure having two contacts and a binding post all exteriorly located, said structure being constructed to constitute a housing; a sheet condenser located in said housing; condenser-clamping means also located in said housing; and electrical connections to permit inclusion of different portions of the condenser between the binding post and the respective 30 exterior contacts.
11. An electrostatic device which comprises an insulating housing; a sheet condenser located therein; two contacts located exteriorly on the housing; means for clamping the condenser; means for securing the clamped condenser to the housing; a binding screw combined with said securing means; and means electrically connecting the condenser with the contacts and binding post.
12. An electrostatic device which comprises a two-part insulating member constructed to form a housing; a condenser therein and mounted on one of said parts; two exterior contacts mounted on the second 35 part; a binding post mounted on the first part; means for securing the two parts of the insulating member together; condenser clamping means and electrical connections between the binding post, condenser and the two contacts.
13. An electrostatic device which comprises an insulating member of larger diameter at one end than at the other; the portion of larger diameter having a hollow interior; a screw-sleeve and an end contact 40 mounted on the end of smaller diameter; a condenser located in the hollow space in the portion of larger diameter; means clamping the condenser; a binding post on the portion of larger diameter; two electrical connections 45 extending from the condenser through the interior of the portion of smaller diameter to the sleeve contact and end contact respectively; and an electrical connection between the condenser and the binding post.
14. An electrostatic device which comprises two insulating members constructed to form a housing; a condenser supported by one of said members and located in the housing; a binding post on the same insulating member and electrically connected with the condenser; means clamping the condenser in the housing; and a screw-sleeve and end contact for socket connection and carried 50 and supported by the other insulating member.
15. An electrostatic device which comprises an insulating plug having one end of larger diameter than the other and constructed to form a housing in the larger end; a screw-sleeve contact and an end contact on the portion of smaller diameter; a condenser in said housing; means clamping the condenser; and a binding post on the portion 55 of larger diameter and in electrical connection with the condenser.
16. A condenser and binding post construction for an insulated communication contact plug, which comprises clamping means for the condenser inside the plug; a threaded rod secured to the clamping means and extending through the insulating plug from interior to exterior thereof; and a screw on the rod outside the plug to secure the clamped condenser to the plug; the end of the threaded rod beyond the screw being threaded to receive a binding post.
17. An electrostatic device comprising an insulating casing enclosing a housing space and having one end plug-shaped, provided with exteriorly exposed socket contacts; and formed with a hollow extending longitudinally to one of said socket contacts; an electrical condenser and a metal member in said housing space; a lead from one end terminal of the condenser to said metal member; a rod extending thru said hollow in the plug end of the casing, holding one of said socket contacts to the plug and mechanically and electrically connected to said metal member; means electrically connecting the other socket contact with the other end terminal of the condenser; and a binding post mounted in said casing, extending exteriorly there-

of and electrically connected with a portion of the condenser intermediate its said end terminals.

18. An electrostatic device comprising an insulating casing enclosing a hollow space and having one end plug-shaped, provided with exteriorly exposed socket contacts and formed with a hollow extending longitudinally to one of said socket contacts; an electrical condenser in said housing space; a lead extending from one end terminal of the condenser thru said hollow to said contact; means electrically connecting the other end terminal of the condenser to the other socket contact; and a binding post mounted on said casing, extending exteriorly thereof, and electrically connected with a portion of the condenser intermediate said end terminals.
19. An electrostatic device comprising an insulating casing enclosing a housing space and having one end plug-shaped, provided with exteriorly exposed socket contacts and formed with at least two hollows extending longitudinally to said socket contacts; an electrical condenser and a metal member in said housing space; a lead from one end terminal of the condenser to said metal member; a rod extending thru one of said longitudinal hollows in the plug end of the casing, holding one of said socket contacts to the plug and mechanically and electrically connected to said metal member; a binding post mounted in said casing, extending exteriorly thereof and electrically connected with a portion of the condenser intermediate its end terminals; and a lead extending from the other end terminal of the condenser thru another of said longitudinally extending hollows to said other socket contact.
20. An electrostatic device comprising an insulating casing formed at one end with a

condenser-housing space and at its other end as a contact plug adapted to cooperate with ordinary electric lighting sockets; an electrical sheet condenser in said housing space and arranged with its sheets substantially in the plane of the radii of the plug end permitting a relatively short thickness of the housing space and over-all length of the casing; the radius of the housing space being at least of the order of the radius of the plug end permitting adequate area of the condenser sheets; electrical connections extending from the end terminals of the condenser thru the plug end to the plug contacts; and an electrical connection extending from an intermediate terminal of the condenser thru the insulating casing to the exterior thereof.

21. An electrostatic device comprising a sheet condenser, an insulating casing therefor, and a metal clamping device for the condenser; three condenser terminal-leads extending from the condenser thru said insulating casing; one of said terminal leads being connected to said clamping device; and three sets of armature sheets projecting beyond the condenser dielectric sheets, one set connected to said clamping device, and the other two being connected respectively to the other two terminal leads.

22. An electrostatic device comprising a sheet condenser, a clamping device therefor, and three terminal leads one of which is connected to said clamping device; said clamping device being connected to both ends of a set of armature sheets of the condenser extending in opposite directions beyond the dielectric sheets; and the other two terminal leads being connected respectively to sets of armature sheets projecting respectively in opposite directions beyond the dielectric sheets.

W. STUART WEBSTER.
